Wm. Shell.

INVENTOR,

Emma G. Gilman,
John DeWitt,
ATTORNEY

UNITED STATES PATENT OFFICE.

EMMA G. GILMAN, OF PATERSON, NEW JERSEY.

DUSTER.

1,392,633.

Specification of Letters Patent. Patented Oct. 4, 1921.

Application filed April 8, 1921. Serial No. 459,695.

To all whom it may concern:

Be it known that I, EMMA G. GILMAN, a citizen of the United States, residing at Paterson, in the county of Passaic and State 5 of New Jersey, have invented certain new and useful Improvements in Dusters, of which the following is a specification.

The object of this invention is to provide a duster of the class having a handle which 10 can be manufactured and sold at comparatively little cost and in which the dusting fabric, composed of one or more cloths or other suitable material, will be held securely in proper arrangement for dusting and so 15 that it may be readily removed whenever it becomes soiled and a fresh one substituted. To this end the handle consists of a suitable length of wood having one end portion 20 formed into a grip or handle proper and the other end portion formed with a longitudinal groove which reaches to its free end, and in the inner end of the groove an elongated flexible device, as a cord, is permanently attached, the other end of the cord 25 having a fastening, as a loop or eye to fit over a stud or pin arranged at an exterior point of and on the handle and so detachably hold the fold or folds of the fabric, which straddle said flexible device, in the groove.

30 In the drawing,

Figure 1 is a perspective view of the improved duster;

Fig. 2 is a side elevation, showing the grooved portion of the handle and the fabric 35 in longitudinal section; and

Fig. 3 is an elevation looking from the left in Fig. 2.

The handle α is composed of a suitable length of wood, one end portion of which is 40 suitably shaped to provide a grip or handle portion b and the other end portion of which is formed with a longitudinal groove c , so that it is in effect U-shaped in cross section.

The fabric d is in the present case shown 45 as consisting of several layers of cloth, say in the form of squares, which are folded on one diameter. The fold reposes in the groove c of the handle, so that the free edges of the fabric hang therefrom.

50 The securing device is an elongated flexible member e , say of cord or wire. It is secured permanently to the handle at one end and detachable thereto at its other end, lying in and extending longitudinally of the

groove and being straddled by the folded 55 fabric and holding the same clamped against the bottom of the groove. It is permanently secured at the one end by having a loop e' formed therein and penetrated by a pin f which is driven through the handle and traverses the groove near its inner end; the device e is detachably secured at its other end by having a loop or eye e^2 thereon which is adapted to be slipped over a stud g preferably having a head, the stud being driven 65 into the handle at the exterior thereof. The device e is protected against being worn away where it projects from the groove at the free end thereof and is then returned to engage the stud by providing a notch h 70 to receive the same in the free end of the handle.

When the fabric becomes soiled or worn in use, the device is detached from the stud and then a freshly folded fabric is inserted 75 in the groove in the manner shown in the drawing, the device e is placed in the fold of the fabric and its free end again attached to the stud.

I am aware that it is old in the art of 80 brushes, dusters, mops and the like to provide a handle with a longitudinal groove and secure folds of fabric or equivalent in the groove by a member which is straddled by the fabric; but in any previous construction known to me said member is stiff and permanently secured to the handle and furthermore adds considerably to the weight of the device, and in these and other respects differs from my invention, which I claim as 90 follows:

1. In combination, an elongated handle member having a groove formed therein and extending to one end thereof, a fabric having a fold formed therein and having such 95 fold lying in the groove, and an elongated thin flexible securing device for the fabric secured at one end thereof permanently to the handle and in the groove and detachably secured at its other end to the handle exterior of the groove and straddling and thereby holding the fabric clamped against the bottom of the groove.

2. In combination, an elongated handle member having a groove formed therein and extending to one end thereof and also having a notch in said end communicating with the groove, a fabric having a fold formed 105

therein and having such fold lying in the groove, and an elongated taut flexible securing device for the fabric secured at one end thereof to the handle and in the groove and 5 extending lengthwise of and in the groove and having its other end portion bent around said end of the handle and lying in said notch and detachably secured to the handle exterior of the groove, said device straddling and thereby holding the fabric 10 clamped against the bottom of the groove.

In testimony whereof I affix my signature.

EMMA G. GILMAN.
